DENT FOR LOOM REEDS

George A. McFetters, Greensboro, N.C., assignor to Greensboro Loom Reed Company, Inc., Greensboro, N.C., a corporation of North Carolina

Filed Aug. 10, 1959, Ser. No. 832,832

5 Claims. (Cl. 139—192)

This invention relates generally to dents for loom reeds and more particularly to improved dents adapted to reduce friction and static electricity upon the warp thread guided thereby.

All known prior attempts to reduce friction of the dents against the warp threads guided thereby have involved the use of specially constructed dents in which the cross-sectional configuration of the dents was unusual or involved positioning the dents in the reed frame so that they extend between the warp threads at an unusual angle.

It is the primary object of the present invention to provide improved dents for a loom reed which are adapted to reduce friction and static electricity upon the warp threads guided thereby while utilizing dents having a conventional cross-sectional configuration and maintaining the dents in a conventional position in the reed frame.

It is another object of the present invention to provide friction and static electricity reducing dents for a loom reed by utilizing a friction and static electricity reducing surface on the faces of the reed dents which engage the warp threads guided thereby.

It is still another object of the present invention to provide friction and static electricity reducing reed dents which may be economically produced and assembled in the conventional manner heretofore used to assemble smooth-faced reed dents of the conventional type.

Some of the objects of the invention having been stated, other objects will appear as the description proceeds, when taken in connection with the accompanying drawings, in which—

Figure 1 is a fragmentary front elevation of one end of a loom reed frame with the improved reed dents of the present invention supported therein;

Figure 2 is an elevation looking at the righthand end of Figure 1;

Figure 3 is an enlarged side elevation of a fragment of the reed dent shown in Figure 2, encompassing substantially the area enclosed by the dotted rectangle indicated at 3 in Figure 2;

Figure 4 is a greatly enlarged horizontal sectional view through the reed dents shown in Figure 1 and being taken substantially along the line 4—4 in Figure 1;

Figure 5 is a view similar to Figure 4 except showing a modified form of reed dents in which the friction and static electricity reducing finish is applied to a dent which is oval in cross-section; and

Figure 6 is a greatly enlarged fragmentary view of the area encompassed by the dotted rectangle 6 in Figure 4 and illustrating the thread contacting the friction and static electricity reducing surface of a reed dent, which in this instance has been plated.

Referring to Figures 1 and 2, the loom reed is broadly indicated at 10 and comprises an upper reed back 11, a lower reed back 12 and end members 13, only one of which is shown. The ends of the upper and lower reed backs 11 and 12 are suitably secured to the end members 13 in a conventional manner. A plurality of spaced apart, parallel reed dents, broadly indicated at 15, are

2

supported at opposite ends of the upper and lower reed backs 11 and 12 in a conventional manner. If desired, the upper and lower backs 11 and 12 may be covered with respective sleeves 16 and 17 to protect the ends of the reed dents 15.

As shown in Figures 3, 4 and 6, the reed dents 15 comprise a body portion 19 which is substantially rectangular in cross-section and the body portion 19 is provided with friction and static electricity reducing, irregular surfaces 20. The irregular surfaces 20 may be produced in a number of ways, in the present instance a matte finish has been obtained by a blasting process where loose abrasive material was blasted against the sides of the reed dent material by liquid and air pressure. This blasting process produces a smoothly pitted surface in which the amount of irregularity will vary in accordance with variations in the type of metal processed, the type of abrasive used and the pressure of the liquid and air.

The irregular surfaces 20 may be plated with a thin layer of chrome or the like, indicated at 21 in Figure 6. The chrome plate layer 21 prevents corrosion of the metal and reduces wear of the reed dents 15 by the thread T as they engage the opposite sides of the reed dents 15. As shown in Figure 6, the layer of chrome 21 is of uniform thickness and conforms to the irregular surface 20 of the reed dent 15. It is believed that friction is reduced because only the outwardly projecting portions of the surface 20 engage the surface of the thread T.

Referring to Figure 5, there is shown a modified form of reed dent, indicated broadly at 15' which comprises a body portion 19' that is oval in cross-section and has a roughened or irregular surface 20'. The rectangular reed dent 15, shown in Figure 4 and the oval reed dent 15' shown in Figure 5, are both conventional except for the respective irregular surfaces 20 and 20' and it is to be understood that the irregular surfaces may also be applied to other conventional types of reed dents which have various cross-sectional configurations.

As heretofore stated, the present invention is of particular value when weaving threads of synthetic man-made fibers, however, matte finish reed dents may also be used to an advantage when weaving other types of thread. When weaving a continuous filament man-made thread, in addition to reducing the amount of friction and the static electricity built up in the thread, the matte finish reed dents also add protection against filament breakage and scuffing damage. Matte finish reed dents may also be used to an advantage when weaving threads formed of staple length fibers, whether the fibers be natural or man-made fibers, and in addition to reducing the amount of friction and static electricity built up in the thread, the matte finish dents lessen the amount of fly accumulation, cause less distortion of the fibers in the threads, and provide better tension uniformity.

In practice, it has been found that matte finish reed dents reduce friction thirty to fifty percent and substantially reduce the amount of static electricity built up in the threads. Heretofore, it has been almost impossible to weave Dacron continuous filament threads because of the large amount of static electricity built up in the threads and it has been found that this type of thread may be woven satisfactorily by using matte finish reed dents.

It has also been found that when conventional smooth faced reed dents are used, the coefficient of friction increases rapidly with increased speed of the reed and the resulting speed at which the threads guided thereby are engaged by the reed dents of the reciprocating reed. However, when matte finish reed dents are used, the coefficient of friction increases only slightly as the speed of the reed increases. Thus, it is possible with the use

of matte finish reed dents to operate the weaving loom at a faster than normal rate of speed while maintaining a low coefficient of friction and a small amount of static electricity.

Throughout the specification, the terms irregular, smoothly pitted and matte have been used to identify the finish on the surface of the improved reed dents. This finish might also be described by comparing the appearance of smooth surfaced conventional reed dents with the appearance of the irregular surface of the improved reed dents when viewed with the naked eye. The surface of conventional reed dents is macroscopically smooth, shiny and specular while the surface of the present improved reed dent is macroscopically rough and non-specular and presents a dull gray-like metallic appearance to the eye.

However, a properly prepared matte-finish for the reed dents should be semi-dull in appearance and smooth to the touch. Actually a flat dull finish is undesirable. The desired finish may best be described by reference to a standard gauge for measuring surface roughness by the heights of the irregularities with respect to an average line with the heights being expressed normally in micro-inches. In most instances the root-mean-square (R.M.S.) value is used which value is equal to the square root of the sum of the deviation of individual points above or below the average line divided by the number of points measured. The standard gauge employed for measuring surface roughness is a Profilometer in which a sharp diamond stylus is moved at a constant rate across the surface to be measured and the rise and fall of the stylus are amplified electrically and indicated on a meter which is arranged to indicate directly the R.M.S. value of the surface. This apparatus is manufactured by Micrometrical Manufacturing Company of Ann Arbor, Michigan.

It has been determined that when the coefficient of friction is plotted as an ordinate against surface roughness in micro-inches as the abscissa, for nylon particularly, the polished or shiny chrome surface range is indicated between 0 and 20 R.M.S., and the matte finishes will range from 20 to 200 R.M.S. The preferred range for the macroscopically rough and non-specular matte surface will lie between 70 and 200 R.M.S. depending on the denier or other properties of the thread to be woven.

By providing the reed dents with a matte finish, the amount of friction between the threads guided by the dents and the amount of static electricity built up in the threads are greatly reduced and additionally the threads are less likely to be damaged. It is preferred that the reed dents be finished with the matte surface before they are assembled in the reed frame and this

may be accomplished in a continuous conventional blasting process in an economical manner.

In the drawings and specification there has been set forth a preferred embodiment of the invention and, although specific terms are employed, they are used in a generic and descriptive sense only and not for purposes of limitation, the scope of the invention being defined in the claims.

I claim:

1. An improved reed for a loom having a plurality of spaced apart metal dents between which warp threads are adapted to pass, the improvement comprising each dent having a macroscopically rough metallic surface provided with a non-specular, smoothly abraded, matte finish.
2. An improved reed for a loom having a plurality of spaced apart metal dents between which warp threads are adapted to pass, the improvement comprising a chrome coating on each dent with the surface of said coating being macroscopically rough, and said surface of said coating having a non-specular, smoothly pitted, matte finish.
3. An improved reed for a loom having a plurality of spaced apart metal dents between which warp threads are adapted to pass, the improvement comprising each dent having a macroscopically rough surface provided with a non-specular, smoothly pitted, matte finish, and a chrome coating on each dent having its outer surface conforming to the underlying surface of the dent.
4. An improved reed for a loom having a plurality of spaced apart metal dents between which warp threads are adapted to pass, the improvement comprising each dent having a matte-finish chrome surface with a Profilometer rating of R.M.S. 20 to 200.
5. An improved reed for a loom having a plurality of spaced apart metal dents between which warp threads are adapted to pass, the improvement comprising each dent having a matte-finish chrome surface with a Profilometer rating of R.M.S. 70 to 200.
